Filed July 7, 1930

FIG. 5

Hugh J. Ellis
By Chester W. Brown
his Attorney

UNITED STATES PATENT OFFICE

HUGH J. ELLIS, OF BERWYN, ILLINOIS

MICROPHONE

Application filed July 7, 1930. Serial No. 466,195.

- The present invention relates to microphones employed to broadcast radio, and one of the objects is to provide a microphone adapted to more satisfactorily transmit the sound waves which contact with the diaphragm thereof producing better volume, tone-quality, clearness with freedom from distortion throughout the range of vibrations employed.
- Another object is to provide a microphone which may be easily and quickly adjusted to obtain the best results with such microphone under the varying conditions of operation.
- Another object is to provide a microphone in which the parts comprising said microphone may be easily and quickly assembled and accurately adjusted to any requirements specified.
- Another object is to provide microphones which may be readily adjusted to the highest efficiency where several are used conjointly, or all may be adjusted to a uniform resistance, if desirable.
- Another object is to provide a microphone in which the parts cannot be short-circuited in adjusting or handling, or by reason of atmospheric conditions.
- With the above, and other objects in view, which will more particularly appear from the following specification and the accompanying drawing, in which like numerals of reference refer to the same part throughout the various views, and in which
- Figure 1 is a front elevation of the microphone.
- Figure 2 is a side elevation taken from the right in Figure 1.
- Figure 3 is a section view taken along the line 5—5 in Figure 1, showing the front portion.
- Figure 4 is a section view of the rear portion taken along the line 5—5 in Figure 1.
- Figure 5 is a detail section view of the parts 12, 14, 16, 17, and 19.
- My improved microphone, shown and described herein, is designed to provide the maximum of efficient service with freedom from troubles and is simple and convenient in its arrangement of parts and assembly thereof, and has the added advantage of easy and quick adjustment to meet the varying conditions and requirements for the transmission of sound, especially for radio broadcasting.
- The microphone shown herein, consists of a frame, formed by attaching front and rear sections 1 and 2 together by means of suitable screws 4, 4 to form a housing. The diaphragm 3 is placed between the two sections 1 and 2, and has holes through which the screws 4, 4 readily pass when the diaphragm is properly assembled between said sections 1 and 2. A large threaded central opening is formed in the front section 1, and the threaded ring 25 is provided adapted to be screwed into said opening until the ring contacts with the diaphragm 3. This ring 25 has a circular ridge 26 on its rear side, said ridge being semi-circular shape in cross section, which is adapted to engage the diaphragm 3 and press it rearwardly whenever the ring 25 is turned back sufficiently in said threaded opening in section 1. In the forward surface of the section 2 is formed a circular co-acting groove 27 which registers with the ridge 26, and is adapted to receive the diaphragm as it is forced backward by the ring 25. By this means, the diaphragm being held firmly between the sections 1 and 2, may be tightened to any desired tension, by turning the ring 25 until it engages the diaphragm to produce the tension desired.
- At the middle portion of the ring 25 there is provided a circular hub 10, extending outwardly perpendicular to the face of the ring, a suitable distance for the purpose described. This hub 10 is attached to the outer portion of section 1 by means of a plurality of radially extending members 11, 11, 11 which form a web supporting the hub 10 centrally of said ring, with suitable openings between the radial members to permit sound waves passing therethrough to contact with the diaphragm 3.
- The hub is provided with a centrally threaded opening to receive the threaded bushing 12. This bushing is preferably made of some suitable insulating material, as bakelite. A central threaded opening is provided at 13 in said bushing, and within

this opening is the sleeve 14. This sleeve 14 is provided with a central threaded opening 15, within which is the screw for the binding post 16 at the outer end, and the threaded stem of the microphone button mounting 17 at its inner portion. The microphone button 19, made of carbon or other suitable material, is securely attached to the inner end of the mounting 17. The inner end of the bushing 12 is formed into a cup shape extending toward the diaphragm a sufficient distance to enclose the microphone button, and part of the thickness of the felt washer 20 disposed within said cup shaped portion, in contact with the microphone button. Said washer 20 is designed to form a recess between the microphone button and the diaphragm 3 for the reception and retention of the carbon granules 21 placed therewithin. The washer 20 is preferably made of yielding material, to permit it to be compressed, as the bushing 12 is moved rearwardly to compress the carbon granules between the microphone button and the diaphragm. A set screw 24 is provided to lock the bushing in any position to which it has been adjusted, against accidental movement from said position.

The forward surface of the rear section 2 is provided with a recess at 22 to avoid possibility of the diaphragm coming into contact with said section member at any portion of the stretched central portion thereof. At the middle portion of the rear member 2 is provided a perpendicularly extending hub 23. This hub has a centrally threaded opening similar to hub 10 in which a bushing similar to 12 is threaded. The bushing in turn has a central opening with a sleeve, binding post, microphone button mounting, microphone button, felt washer and carbon granules all similar to parts 13, 14, 15, 16, 17, 19, 20, 21 above described, and a set screw similar to 24 for the same purpose.

Binding post nuts may be attached to two of the screws 4, 4 for convenience in attaching one of the operative line wires (not shown) and the other line wire may be connected to the binding post screws 16, 16.

To assemble this microphone, the diaphragm is placed between the sections 1 and 2 with the screw holes in alignment. Screws 4, 4 are inserted and screwed down tight to bind the said diaphragm firmly between said sections 1 and 2. The ring 25 is next screwed into the forward section 1, and turned until it engages the diaphragm with any tension desirable. The parts 14, 16, 17, 19, 20 and 21 are properly assembled with the bushing 12, and the bushing is then screwed into the hub 10 until the washer 20 contacts with the diaphragm. By turning the ring 25 forward or back the tension on the diaphragm may be increased or decreased, as desired for most efficient service, and by turning the bushings forward or back, the pressure upon the carbon

granules may be increased, or decreased, to increase or decrease the resistance to the electric current passing therethrough. By these means, the said microphone may be easily and quickly adjusted to any desired resistance, or to any resistance which gives the best results, or two or a plurality may be adjusted to the same identical resistance, when desired.

Having thus described my invention, what I claim, and desire to secure by Letters Patent, is the following:—

In a device of the class described, the combination of a frame composed of two sections secured together by means of screws, a diaphragm rigidly mounted between said sections, said diaphragm having perforations through which said screws extend, an annular member adjustable axially within the frame and contacting said diaphragm for stretching the latter, a centrally disposed threaded opening in the frame on each side of said diaphragm, externally threaded bushings of insulated material adjustably mounted in said opening, each of said bushings being recessed to form a resistor cup, an electrode mounted in the bottom of each of said resistor cups, a felt washer mounted in each of said resistor cups and in contact with said diaphragm, carbon granules retained in the central opening in each washer and in contact with the diaphragm, and means for locking said bushings in adjusted position.

In testimony whereof, I have duly signed the foregoing specification.
